CLAIM

The ornamental design for a cordless microphone, as shown and described.

DESCRIPTION

1. Cordless microphone

1.1 is a front view of a cordless microphone showing my new design;

1.2 is a rear view thereof;

1.3 is a rear view thereof, wherein the clip is rotated in an alternate position;

1.4 is a left side view of the design shown in FIG. 1.1;

1.5 is a right side view thereof;

1.6 is a top view thereof;

1.7 is a bottom view thereof;

1.8 is a bottom, rear, and left side perspective view thereof; and

1.9 is a top, front, and right side perspective view thereof.
